Primary Examiner — Cynthia R Underwood(74) *Attorney, Agent, or Firm* — LambertIP(57) **CLAIM**

The ornamental design for a torque limiting nut, as shown and described.

DESCRIPTION

FIG. 1 is a perspective view of a torque limiting nut, showing my design.

FIG. 2 is another perspective view thereof.

FIG. 3 is a top view thereof.

FIG. 4 is a bottom view thereof.

FIG. 5 is a side view thereof.

FIG. 6 is another side view thereof.

FIG. 7 is a cross-sectional view thereof, taken along line 7-7 in FIG. 3; and,

FIG. 8 is a cross-sectional view thereof, taken along line 8-8 in FIG. 3.
